Dec. 1456

Daniel M. Scypes & Samuel Smith, of Springville, Penn.

Assignors to

Smith, Francis and Wells, of same place.

Whole No. 1456. Letters Patent No 91. dated July 23. 1861.

The schedule referred to in these Letters Patent and making part of the same.

To all whom it may concern:

Be it known that we, D. M. Scypes and Samuel Smith, both of Springville, County of Chester, State of Pennsylvania, have invented or produced a new and original design for a cooking stove, termed the Chilion, and we do hereby declare the accompanying drawing with the following explanation of the same, to form a full, clear and exact description of the said design.

Fig. 1. of the drawing represents the stove in perspective.

Fig. 2. a transverse section of the top plate on the line 1, 2. Fig. 1.

Fig. 3. a transverse section of the side plates on the line 3, 4. Fig. 1.

The side plate A, which is edged with a plain moulding, has a large oven door a, and a smaller door b, the former being edged with a plain moulding inclosing the scrolled and foliated ornament represented in the drawing, the space within this ornament containing the representation of a bird with out spread wings near a nest which contains a number of eggs. the smaller door b being also edged with a plain moulding within which is a scrolled and foliated ornament, inclosing a group of flowers and leaves.

The upper front plate B, is ornamented at the opposite edge in the manner clearly represented in the drawing, and has a plain moulding forming a panel with in which is a foliated ornament intertwined at one upper corner with a plain scroll containing the word "Chilion" in raised letters, and at the opposite upper corner with a similar scroll containing the word "Complete"; in the centre of the panel is a vase containing a group of leaves, flowers, fruits &c.

The lower front plate D, has two doors each of which is edged with a plain moulding inclosing ornaments of a character similar to that of the ornaments on the small door b, of the side plate, and near the top of this lower front plate is a falling door e, having, near its upper edge, the foliated ornaments shown, and below the latter a panel containing the words "Smith, Francis and Wells". Below this falling door is another

Des. 1456

panel containing the words "Springville Chester Co. Pa." The ornaments on the opposite vertical edges of this plate are clearly shown in the drawing.

The upper top plate E is edged with a plain moulding excepting in front, which has the ornamented moulding shown, the lower top plate E' being plain with the exception of the mouldings on the edge, the form of which will be seen on reference to Fig. 2.

The drawing will explain the character of the design and ornamentation of the legs.

We claim the ornamented figures and forms represented in and by the accompanying drawing and forming together an ornamental design for the plates of a cooking stove.

In testimony whereof we have signed our names to this specification in the presence of two subscribing witnesses.

Witnesses.
